L. B. CASTETS

EVAPORATING APPARATUS

Filed Oct. 23, 1922

Inventor
Louis B. Castets.
By Decatur Orth Atty.

UNITED STATES PATENT OFFICE.

LOUIS BARTHELEMY CASTETS, OF BENEJACQ, FRANCE.

EVAPORATING APPARATUS.

Application filed October 23, 1922. Serial No. 596,468.

To all whom it may concern:

Be it known that I, LOUIS BARTHELEMY CASTETS, citizen of the Republic of France, and resident of Benejacq, Basses-Pyrénées, 5 in the said Republic, manufacturer, have invented certain new and useful Improvements in Evaporating Apparatus; and I do hereby declare the following to be a full, clear, and exact description of the invention, 10 such as will enable others skilled in the art to which it appertains to make and use the same, reference being had to the accompanying drawings, and to letters or figures of reference marked thereon, which form a part 15 of this specification.

The apparatus forming the object of my invention is designed to distill, evaporate or concentrate all and any bodies or substances of a nature to undergo such operations and 20 is based on the phenomenon of emulsive propulsion, a phenomenon brought about by the running of the material under treatment in a direction contrary to that of steam (counter-flow). My apparatus can work under 25 normal or under reduced pressure, according to the requirements of the bodies to be treated.

In order to make my invention more clearly understood I have illustrated, as an example, an embodiment thereof, namely, an apparatus designed to work under normal pressure, in and by the appended drawing, wherein: Figure 1 is a vertical section of my apparatus and Figure 2 is a plane view of 35 the same with certain parts broken off.

My apparatus comprises: a box having an upper compartment *a* to receive the material to be treated, such box being fitted with a perforated plate *b* above the bottom *c* 40 of the upper compartment *a* and resting on a second compartment *d*. On the sloping bottom of the latter which conserves the heat is set a flat rectilinear coil *e'* to *e''* the coils of which are surrounded with or 45 cased in a steam circulation double envelope or casing *f*.

An upward tube *h*, running from section *e''* of the coil, leads to a chamber *n* which has a heating plate *g* provided with a steam 50 circulation box *h* and carries a swan neck *i* opening into a condenser of any sort or type, whether a surface condenser or a mixture condenser. The condensated products are led into suitable containers, not shown.

55 In the drawing, direction of the stream flow is indicated by a full line arrow and

direction of the run of material by a dotted line arrow.

The working is as follows:

Steam is fed into steam box *h* through 60 nozzle *j* and, after having gone through the whole length thereof, passes into double casing *l* of tube *k* through tube *m*, circulating therefrom through jacket or casing *f* of coil sections *e'* to *e''* and getting out through a blow-off located on section *e'* fitted with a nozzle *o*. The material to be treated is introduced into box *a* and, through the holes in perforated plate *b* which retains whatever impurities the material may contain, 70 accumulates in the space between said plate *b* and bottom *c*.

Through tube *p* connecting nozzle *q* with coil section *e'* and provided with a control cock *r*, the material is introduced into the 75 coil, through all the members of which it runs, to go up through tube *k* and discharge on to heated plate *g*. From there the vapours escaped are led by swan neck *i* to the condenser and the liquid material flows 80 out through outlet nozzle *s*.

Of course the number of coil turns or sections is not limited and my apparatus can be built with several superimposed coils.

The purpose of tubes *t*, *u*, *v*, is to permit, 85 in certain cases, agents adapted to foster separation of the various components of the material under treatment to be introduced into the coil.

Having now particularly described and 90 ascertained the nature of my said invention as well as the manner in which the same is to be performed, I declare that what I claim is:

1. In an evaporator, the combination with 95 a box having an upper and a lower heat conserving compartment: of an inclined, jacketed serpentine in the lower compartment, the interior of said serpentine connected to the upper compartment, means to admit steam to the jacket near the discharge end of said serpentine and an evaporating plate onto which said serpentine discharges 100 from its upper end.

2. In an evaporator, the combination with 105 a box having an upper compartment and a lower heat conserving compartment and a screen in said upper compartment above the bottom thereof; of an inclined, jacketed serpentine whose lower receiving end enters the bottom of said upper compartment below 110 said screen, a hot plate, a steam box below

- the same, and means to connect said steam box and the upper end of said jacket, the upper end of said serpentine discharging onto said plate.
- 5 3. In an evaporator, the combination with a box having an upper open compartment and an inclined screen above the bottom of said upper compartment; of a heat conserving lower compartment and a jacketed, inclined serpentine in the lower compartment connected at its lower receiving end to said
- 10

upper compartment below said screen, a chamber having a hot plate forming its bottom, a steam box covered by said plate and means to connect said box with the 15 jacket at its upper end, whereby said serpentine is heated by a counter current of steam and the upper compartment is heated from the lower compartment.

In testimony that I claim the foregoing as 20 my invention, I have signed my name.

LOUIS BARTHELEMY CASTETS.
